U.S. Cl. D23—39

FIG. 3

FIG. 4

FIG. 1

FIG. 2

FIG. 1 is a front elevational view of an indicator post for a valve showing our new design, the post being illustrated as if the valve is in the shut position;

FIG. 2 is a side elevational view of FIG. 1;

FIG. 3 is a top plan view thereof; and

FIG. 4 is a front elevational view thereof, the post being illustrated as if the valve is in the open position.

The broken line representation of a support post, a locking hasp and indicia is for purposes of illustration only.

We claim:

The ornamental design for an indicator post for a valve, substantially as shown and described.
